CLAIM

I claim the ornamental design of the dispenser jar, as shown and described.

DESCRIPTION

FIG. 1 is a perspective view of the dispenser jar;
FIG. 2 is a front view thereof;
FIG. 3 is a rear view thereof;
FIG. 4 is a first side view thereof;
FIG. 5 is a second side view thereof;
FIG. 6 is a top view thereof;
FIG. 7 is a bottom view thereof; and,
FIG. 8 is another perspective view showing the dispenser jar.
The broken lines in the drawings represent environmental
structure and form no part of the claimed design.

1 Claim, 7 Drawing Sheets
